UNITED STATES PATENT OFFICE.

ARNOLD FRAUCHIGER, OF SAN FRANCISCO, CALIFORNIA.

DIRECTION-INDICATOR.

1,103,498.

Specification of Letters Patent. Patented July 14, 1914.

Application filed January 18, 1913. Serial No. 741,665.

To all whom it may concern:

Be it known that I, ARNOLD FRAUCHIGER, a citizen of the United States, residing in the city and county of San Francisco and State of California, have invented new and useful Improvements in Direction-Indicators, of which the following is a specification.

This invention relates to an indicator.

10 The main object of this invention is to provide a simple, practical and compact indicating mechanism, which is particularly adapted for application to automobiles and like vehicles.

15 Another object of the invention is to provide means controlled by the operator of the car for the purpose of indicating to pedestrians in general the intended directions of the car.

20 A further object of the invention is generally to improve this class of apparatus so as to decrease the difficulty of the traffic problem in crowded districts.

The invention consists of the parts and 25 the construction and combination of parts as hereinafter more fully described and claimed, having reference to the accompanying drawings, in which—

Figure 1 is a front view partly broken 30 away, showing the indicating arm and operating mechanism and also the wiring diagram of the apparatus. Fig. 2 is a cross section on the line X—X of Fig. 1. Fig. 3 is a front view of a radiator showing the 35 application of the device.

By referring to the drawings A indicates in general a casing, the front portion of which is designed to resemble an indicating dial as much as possible. Pivotaly mounted upon a double pivot 2 within the casing 40 is an indicator arm 3, weighted in the lower end as at 4, and also slotted as shown at 5, to allow the indicator arm to rock to either one side or another upon the double pivot 2. The rocking of the indicator arm from the 45 central position indicated by dotted lines at 6 in Fig. 1, which it normally assumes when not otherwise acted upon by reason of the counterweight and the position of the 50 double pivot 2, is controlled by a pair of oppositely mounted magnets 7 and 8, either one of which may be energized, to throw the indicator arm to one side or another; the 55 indicator arm being provided with a pair of armature members 7' and 8' for this purpose.

B indicates a storage battery, or like means, which may be carried in any convenient place on the car, and 9 indicates a feed wire which connects with a pair of terminals on the magnets, while the opposite terminals 10 and 10' are connected by the wires 11 and 11' to separate terminals 12 and 13 and a switch 14 mounted in a convenient position near the operator; the third terminal 15 upon which a switch member 16 is mounted being connected by wire 17 to the opposite terminal 18 of the battery B.

From the circuit here indicated it can be seen that the operator may energize 70 either one or the other of the magnets 7 and 8 by simply moving the switch arm 16 to complete a circuit through one or the other of the terminals 12 or 13; or, both may remain deenergized to allow the indicator arm 75 to resume its central position by moving the switch arm 16 to an intermediate position between the terminals 12 and 13.

The dial face of the casing is divided off 80 into four divisions or parts, indicated in Fig. 1, in which 19 indicates a main central segmental part wherein the indicator arm operates; 20 and 21 two side extensions which are faced with colored glass, 20 being colored green while 21 is colored red; 85 these colored parts being provided for the purpose of indicating the right and left hand side of the machine; and a fourth part 22 which is positioned between the extensions 20 and 21, and which is faced with a 90 ground glass, or like material, and is provided for the purpose of displaying the number of the machine as at 23.

The device may be mounted in any convenient position where it can easily be seen 95 by pedestrians in general, but preferably on the forward portion of the radiator, as indicated in Fig. 3, where it may be secured in any suitable manner, as by the bolts 24.

Supposing the car, provided with a direction indicator constructed as previously described, is moving down the right hand side of a street, and that the driver decides to turn down the right-hand side on the first street-crossing—he will then throw the 100 switch arm 16 into contact with the terminal 13 which will close the circuit from the battery through the wires 11 and 9, and magnet 7 and energize this. The energizing 105 of the magnet will attract the armature 7' 110 and indicator arm and rock it into the position shown in Fig. 1, where it registers with

the green colored extension on the dial face. The position of the indicator arm 3 will thus immediately indicate the intended direction of the car. The moment the intended direction of the car has been indicated it will give pedestrians in general, time to decide whether it is feasible or not to cross ahead of the car or give the car the right of way.

Pedestrians are, as a rule, often bewildered by the approach of a car when not knowing the exact direction intended by it. Therefore, it can easily be seen that the moment a sign is displayed indicating the direction of travel of a car, it will make it easier for pedestrians to make a quick decision and step to one side or another.

For the purpose of making the apparatus equally efficient at night, I have provided means for illuminating the dial face of the indicator; the main face in which the indicator arm swings, together with the number displaying face, being illuminated by a suitable light as indicated at 24, while the colored extension surfaces of the dial are illuminated by the separate lights indicated at 25 and 26. One of the lights, as 24, will always be illuminated to show the position of the indicator arm and the number of the machine during the dark hours of the night; being placed on a circuit indicated by the wires 27 and 28; a suitable switch 29 being interposed on this circuit for the purpose of controlling the current flow through same. The light bulbs 25 and 26, provided for the purpose of illuminating the colored extension surfaces of the dial are also placed on the circuit controlled on one side by the wire 27, while the opposite terminals of the lights 25 and 26 are connected by wires 25' and 26' with the terminals of two separate switch members 30 and 31, which in turn are controlled through the rocking movement of the indicator arm, to close the circuit between one or the other of the lights, whichever the case may be; the double pivot member upon which the rocker arm is mounted being connected by a return wire 32, which closes the circuit through the switch 29 back to the battery. Thus it can be seen that by energizing the magnet 7 by throwing the switch arm 16 into contact with the terminal 13 on the switch, the rocker arm will be thrown over to register with the green colored extension surface of the dial. The rocking movement of the lower end of the indicating arm when thrown into this position will close the circuit with the switch member 30 and thus complete the circuit through the wires 27 and 25', switch arm, pivot members, and wire 32, back to the battery. The closing of this circuit by the rocking of the arm thus illuminates the green colored extension surface of the dial, and will immediately indicate to pedestrians that the car intends to turn to the right.

However, if the driver should decide to continue to move in the same direction or in a straight line, he will throw the switch member 16 into an intermediate position between the terminals 12 and 13, which will leave both of the magnets 7 and 8 in a deenergized condition. The counterweight will then restore the indicator arm 3 into normal position, indicated by dotted lines in Fig. 1, where it will immediately close the circuit between both of the switch members 30 and 31, and thus cause both of the colored extension surfaces of the dial to be illuminated. The pedestrian upon seeing the display of both the red and green lights will immediately know that the driver of the car intends to continue in a straight direction.

The switch members 30 and 31 are sufficiently flexible to contact with the lower portion of the rocker arm when this assumes its normal position, indicated by the dotted lines in Fig. 1, and are also sufficiently pliable to yield when the arm is thrown either to one side or another.

The light circuit is here shown as being controlled by the switch 29, which may be thrown off during the light hours of the day, as it is not necessary to illuminate the dial face except after dark. The energizing of the magnets is shown as controlled by the switch 14, which, as before stated, is placed in a convenient position near the operator where he may quickly throw the switch arm 16 into one position or another to indicate the direction of the car.

The apparatus is neat in appearance, simple in construction, and reliable in action, and when positioned as shown in Fig. 3, is not of sufficient size to interfere with the action of the radiator. The materials and finish of the several parts of the apparatus are such as experience and judgment of the manufacturer may dictate.

Having thus described my invention, what I claim and desire to secure by Letters Patent, is—

1. In a direction indicator, a curved indicator face having differently colored extensions at the opposite ends, a weighted pointer having curved connected slots above the center of gravity, pivot pins forming bearings about which the pointer is rockable to one side or the other, armatures fixed to the pointer and inclined co-acting magnets, and means to alternately energize said magnets and rock the pointer to one end or the other of the indicator.

2. A direction indicator comprising in combination a casing, an indicator arm mounted on a double pivot within the casing, slots formed in the arm to allow the arm a free rocking movement upon either pivot, a counterweight on the lower end of the arm, a pair of armature members secured on the arm, a pair of magnets mounted in the

- path of travel of the armature members, a face on the casing over which the arm is adapted to swing, colored extension faces formed on the first named face with which the indicator arm is adapted to be brought into register, and means for energizing one or the other of the magnets to rock the indicator arm into register with one of the colored extensions.
- 10 3. A direction indicator for automobiles comprising in combination a casing, an indicator arm mounted on a double pivot within the casing, curved slots formed in the arm to allow the arm a free rocking movement upon either pivot, a counterweight on the lower end of the arm, a pair of armature members secured on the arm, a pair of magnets mounted in the path of travel of the armature members, a face on the casing over
- which the arm is adapted to swing, colored extension faces formed on the first-named face with which the indicator arm is adapted to be brought into register, means for energizing one or the other of the magnets to rock the indicator arm into register with one of the colored extension faces, means for illuminating the whole face of the indicator, the end portions of the indicator face being capable of illumination in unison with the change of position of the indicator arm. 30
- In testimony whereof I have hereunto set my hand in the presence of two subscribing witnesses.

ARNOLD FRAUCHIGER.
